United States Patent Office

Des. 186,008

Patented Aug. 25, 1959

186,008

HEARTH SHOVEL OR SIMILAR ARTICLE

Willis S. Hobson, Seymour, Ind., assignor to Seymour Manufacturing Company, Seymour, Ind., a corporation of Indiana

Application April 3, 1957, Serial No. 45,567

Term of patent 14 years

(Cl. D81—24)

Fig. 1 is a front view of a hearth shovel or similar article embodying my new design;

Fig. 2 is a side view thereof; and

Fig. 3 is an end view thereof.

The dominant features of the design reside in the portions shown in full lines.

I claim:

The ornamental design for a hearth shovel or similar article, substantially as shown and described.
